INVENTOR.

John E. Hawkins

United States Patent Office.

JOHN E. HAWKINS, OF LANSINGBURG, NEW YORK.

Letters Patent No. 73,006, dated January 7, 1868.

TOY.

The Schedule referred to in these Letters Patent and making part of the same.

TO ALL WHOM IT MAY CONCERN:

Be it known that I, JOHN E. HAWKINS, of Lansingburg, in the county of Rensselaer, and State of New York, have invented a new and improved Toy; and I do hereby declare that the following is a full and exact description of the same, reference being had to the annexed drawings, and the letters of reference marked thereon, making a part of this specification, in which—

Figure 1 is a perspective view of said improved toy, and

Figure 2 is a vertical sectional view of the same—

The same letters having reference to like parts in each of the said figures.

My invention consists in the combination and arrangement of certain parts, in manner substantially as hereinafter fully described, which constitute a toy, and by means of which a ball is projected upward therefrom, which in its descent is caught by the said toy.

To enable others skilled in the art to make my new and improved toy, I now proceed to fully describe the same, as follows:

A, figs. 1 and 2 of annexed drawings, is a stock or handle, which is perforated from end to end, or through its length. Arranged and moving freely within this perforation, is a spindle or rod, B. Attached to the upper end or top of this spindle, is a ball-driver or pocket, C; the top of the aforesaid stock or handle A being hollowed out or made concave, to permit the convex under side of said ball-pocket or driver to fit properly into its said place. The bottom end of said spindle is provided with a driving-knob or button, F. Affixed to the top of the aforesaid stock A, is a cup, D, which encloses and rises in a flaring form above the aforesaid ball-driver or pocket C. This cup D may be made of wire, tin, or of wood, and of a variety of forms or shapes.

The foregoing-described parts, combined and arranged in manner substantially as shown in the annexed drawings, constitute my improved or new toy for projecting balls upward.

E is a ball, made of wood or of other suitable substance, and it is used with the said toy in manner as follows: The toy is held by its stock or handle in a vertical or upright position in one hand. The ball E is then placed in the cup D, and on the ball-driver or pocket C. A quick rap or tap of the other hand is now made or given on the driving-knob or button F, which drives the spindle and ball-pocket C upward, thereby causing the ball E to fly or project out of said pocket C upward, which, in its descent, is caught in the cup D, in readiness to be again projected upward, as before, and so continue, at pleasure, thus making an entertaining and instructive toy for children.

What I claim as my invention, and desire to secure by Letters Patent, is—

The combination and arrangement of the ball-driver or pocket C, and its spindle B, with the stock or handle A and cup D, in manner substantially and for the purpose as herein described.

October 24, 1867.

JOHN E. HAWKINS.
